Patented Sept. 2, 1958

183,469

COMBINED CANISTER AND DETACHABLE MEASURING SPOON

Samuel Sidney Ullman, Los Angeles, Calif.

Application March 6, 1958, Serial No. 49,928

Term of patent 7 years

(CL. D44—6)

Fig. 1.

Fig. 2.

Fig. 3.

Fig. 4.

Fig. 1 is a side elevational view of a combined canister and detachable measuring spoon showing my new design;
Fig. 2 is a side elevational view;
Fig. 3 is a top plan view; and,
Fig. 4 is a fragmentary cross-sectional elevation thereof.
I claim:
The ornamental design for a combined canister and detachable measuring spoon, substantially as shown.
